UNITED STATES PATENT OFFICE

X RAYMOND DODGE, OF HINSDALE, ILLINOIS

SCREW MACHINE

Application filed November 16, 1923. Serial No. 675,037.

As is well understood in the art with the screw machines now on the market, the stock is fed to the machine manually by the attendant, one piece at a time, and when one piece 5 has been passed through the machine and it becomes empty, it then operates idly until the attendant again inserts another piece of stock. The expense of having one man watch each machine sufficiently close to see that the 10 moment one piece of stock has been utilized another is inserted, would be impractical, therefore, in shops running a large number of such machines simultaneously, one attendant is usually delegated to watch or look after 15 several machines, as a result of which the machines are running idly for a considerable portion of the time due to the inability or neglect of the attendant to manually insert additional stock into the machine as the previous 20 pieces are exhausted. Moreover, with the present type of screw machines, after a piece of stock is manually started into the machines by the attendant it is from there on fed by a spring feed chuck and cam lever 25 arrangement which is a constant source of trouble and calls for constant attention of the attendant, which difficulty, as well as the lack of the attendant to manually insert the stock in the machine as soon as the previous 30 one has been exhausted, materially reduces the capacity of the machine, and naturally increases the cost of the articles produced thereby. Another disadvantage of the present type of machine is that the chips from the stock being worked on by the cutting tools rapidly accumulate requiring the attention of the attendant to keep it clean and requires constant removal by the attendant in 35 order to prevent "jamming" of the machine. 40 It is therefore, an object of my invention to provide a screw machine which will overcome these disadvantages.

It is a further object to provide a machine in which the stock is fed therethrough by frictional gravity thus entirely eliminating the old troublesome spring fed chuck and cam lever or its equivalent.

It is a further object of my invention to provide a machine in which the spring, tools 50 and slides are self cleaning without the at-

tention of the attendant and thus prevent all likelihood of the machine jamming, which frequently occurs with the machines now on the market owing to the failure of the attendant to remove the accumulations. 55

It is a further object of my invention to provide new and improved means for adjusting the cutting tools and for bringing the tools to and from the work or stock operated on. 60

It is a further object to provide new and improved means for readily and quickly putting the machine in order upon the completion of the operation of the cutting tools. 65

A further object is to provide new and improved means for readily adjusting or timing one mechanism with respect to another for the different operations. 70

It is a further object of my invention to provide a machine of this type with a magazine which can be loaded with a number of separate pieces of stock at one time and reloaded while the machine is still operating and the pieces of stock automatically fed therefrom without an attendant into the machine successively and continuously without interruption. 75

It is a further object of my invention to greatly increase the capacity of screw machines. 80

The above and other features of novelty, advantages and capabilities, will become apparent from a detailed description of the accompanying drawings in which I have illustrated one form of my invention; but the construction there shown will be understood as illustrative only and not as defining the limits of my invention. 85

Fig. 1 is a side elevational view of a screw machine embodying one form of my invention, with a portion of the feed magazine broken away. 90

Fig. 2 is a top plan view of the same.

Fig. 3 is an end elevational view showing the feed magazine in section and taken substantially on the line 3—3 of Fig. 1, looking in the direction indicated by the arrows. 95

Fig. 4 is a sectional view taken substantially on the line 4—4 of Fig. 3.

Fig. 5 is an end elevational view of the 100

cone pulley taken on the line 5—5 of Fig. 4.

Fig. 6 is an end view of the clutch which cooperates with the cone pulley showing the pawl for engaging with the ratchet on the cone pulley.

Fig. 7 is a horizontal sectional fragmentary view taken on the line 7—7 of Fig. 6.

Fig. 8 is a view taken on the line 8—8 of Fig. 4.

Fig. 9 is an enlarged elevational side view of the trip and locking lever shown in Fig. 8 for cooperating with the clutch, to throw the cam shaft into high speed.

Fig. 10 is a similar view of the same with the parts in slightly different position to lock the trip lever.

Fig. 11 is an enlarged elevational view partially in section of the automatic feed mechanism showing a portion of the feed magazine broken away.

Fig. 12 is an end view of the structure shown in Fig. 11 looking in the direction indicated by the arrows.

Fig. 13 is a view taken on the line 13—13 of Fig. 12.

Fig. 14 is a view taken on the line 14—14 of Fig. 12.

Fig. 16 is a view taken on the line 16—16 of Fig. 14.

Fig. 17 is a view taken on the line 17—17 of Fig. 16.

Fig. 18 is a sectional view of the feed magazine.

Fig. 19 is a plan view of the structure shown in Fig. 18 with a portion broken away.

Fig. 20 is an elevational view of the head plate for the magazine through which the stock is fed.

Fig. 21 is a longitudinal sectional view of the spindle taken on the line 21—21 of Figure 2.

Fig. 22 is an end view of the spindle proper.

Fig. 23 is an enlarged detailed view of the cutting tool partially in section.

Fig. 24 is a sectional view on the line 24—24 of Fig. 23 and,

Fig. 25 is a face view of the cams shown in Figs. 23 and 24.

Referring to the drawings in detail, the bed 10 of the machine is arranged at a substantial angle supported at its lower or forward end by a suitable base 11, and at its rear or elevated end by a satisfactory standard 12. In the embodiment shown, the bed is arranged at approximately a 40 degree angle and I have found after experimenting for a long period of time that the best results are obtained by having the stock pass through the spindle and cutting tools at about that angle. However, I have ob-

tained satisfactory results at various angles from 15 to about 55 degrees.

Suitably mounted on the bed 10, near the upper end thereof and at right angles thereto is a tool feed shaft 13 on which is non-rotatably mounted a taper clutch 14, having an integral sleeve 15 as best shown in Figure 4. Rotatably mounted on this sleeve is a cone pulley 16, the inner face of this pulley being provided with ratchet teeth 17, as best shown in Fig. 5. The clutch 14 carries a pivotally mounted spring pressed pawl 18 designed to engage the ratchet teeth 17 causing the clutch 14 to operate with the pulley 16 when the latter is moving in a clockwise direction. The pulley 16 is driven by means of a belt or the like from a suitable source of power, (not shown) and is provided with stepped grooves so that the speed thereof may be readily changed by shifting the driving belt from one groove to another. The shaft 13 is provided with a suitable slidable clutch 18 which is operated by the lever 18' by throwing such clutch into engagement with the ratchet collar 19 fast to the sleeve 15. It is to be understood that the clutch 14 is non-rotatably mounted on the shaft 13 in any satisfactory manner so that said shaft is caused to rotate with the clutch 14. Near the opposite end of the shaft 13 is a non-rotatably mounted worm 20, which worm is constantly in mesh with a worm gear 21 non-rotatably mounted on the cam shaft 22. This cam shaft is positioned parallel with the bed 10, and rotatably mounted in suitable brackets supported by the bed 10. Non-rotatably mounted on the forward end of the cam shaft 22 is a tail spindle cam drum 23 for operating an adjustable tail spindle head 24 and stock shaft 25 which carries the stock gage 26. The operation and construction of the stock shaft and adjustable tail spindle head may be of any well known form and being well understood in the art a further description of these particular parts is believed unnecessary, with the exception of the means for adjusting the cam on the drum for the purpose of timing the parts operated thereby which will be referred to later.

The spindle 27 (see Figure 21) is rotatably mounted in the housing 27^a supported on suitable brackets 28 on the bed 10. Within the spindle is a friction tube 29, which, by means of the bracket 30 secured to the bed 10 is held against rotation. The stock operated on passes down through this tube by gravity, but gradually and not abruptly, due to the friction of the stock on the inner surface of the tube. This tube, it will be noted terminates short of the lower end of the spindle. The spindle is operated constantly while the machine is being used through the belt wheel 31, which wheel is operatively connected by means of a belt or the like with any

suitable source of power (not shown). In connection with the spindle, I have provided means near the lower end thereof, for gripping the stock and causing it to rotate with the spindle as it is fed to the cutting tools and for releasing such stock when each operation is finished, which means is readily adjustable and can be easily timed to suit the different operations. The means for gripping the stock as best shown in Figs. 21 and 22 consists of a spring chuck 32 preferably constructed of three longitudinal arc shaped members 33 having their inner ends screw threaded into the chuck 34. Near the forward end of the spindle there is mounted between the spring chuck and the outer casing of the spindle a chuck sleeve 35 having its inner outer edge beveled and adapted to cooperate with the outer beveled surface of the spring chuck 32. By sliding this chuck sleeve downwardly or to the right as appears in Fig. 21, the beveled surface thereof slidingly engages the beveled surface of the spring chuck and causes it to contract and tightly grip the stock making it rotate therewith. For moving the chuck sleeve downwardly when it is desired to grip the stock, I have mounted in suitable slots in the casing of the spindle, a pair of chuck fingers 36, which fingers at their downward ends are provided with suitable shoulders 37 adapted to engage the inner end of the chuck sleeve 35. These fingers are also provided at their downward ends with outwardly extending portions having a ball and socket connection with the collar 38, which collar can be readily adjusted on the spindle by means of the adjusting nut 39. The upper ends of the fingers 36 extend outwardly into engagement with the inner surface of the chuck wedge or collar 40. The collar 40 is provided with a peripheral groove with which there is designed to cooperate a bifurcated lever 41, as best shown in Figs. 1 and 2, having suitable pins or rollers adapted to enter the peripheral groove in the collar 40. This lever is fastened to a rock shaft 42, (Figure 21) mounted in a suitable bracket on the bed 10. The inner bifurcated arm is provided with a pin 43 having thereon a roller 44. For rocking this arm and causing the collar 40 to slide back and forth, I have provided a chuck drum 45 which is non-rotatably mounted on the cam shaft 22 and provided with a cam surface 46 adapted when in operation to engage the roller 44. The cam on this drum may be readily and quickly adjusted (as hereafter described) to properly time the gripping and releasing of the stock to suit the different operations. Adjacent to the end of the spindle there are pivotally mounted on the bed 10, by any satisfactory means suitable tool heads 47 (see Figure 23), the upper ends of which are parallel with the axis of the spindle. Secured to the tool heads 47 are suitable cutting or shaping tools, such for

example, as the tools 48 and 49 as shown in Fig. 23.

I have provided means whereby one tool can be set or adjusted independently of the other. For accomplishing this I have mounted a drum 50 on the cam shaft 22, on which drum are mounted cams 51 and 52. These cams are provided with V shaped circular grooves adapted to receive the V shaped tongues (being best shown in Fig. 24) on the disk 53 by means of which they are secured in place by any satisfactory means such as bolts and nuts shown. Rigidly secured to one of the tool heads 47, is a bell crank arm 54 which is provided at its free end with a suitable bracket 55 carrying a roller 56 adapted to cooperate with the cam 52 while the other tool head carries a bell crank arm 57 having at its free end a similar bracket and roller adapted to cooperate with the cam 51. The heads 47 are normally pressed apart by the compression springs 58 mounted on the bolt 59 passing through the lugs 60 formed integrally with the heads 47. With the cam arrangement as just described and as clearly illustrated in Fig. 24, it will be seen that either cam can be readily and quickly adjusted at any desired position so that either head and the tool carried thereby may be set, adjusted and timed for operation independently of the other, by simply changing the position of the cams 51 and 52 with respect to the drum 50.

When the tools are operating on a piece of stock it is necessary that the cam shaft be travelling at a comparatively low speed, but the moment such operation is completed it is extremely important in order to speed up the capacity of the machine that the cam shaft travel at a comparatively high rate of speed so that the parts or members can be readily, quickly and automatically re-set for the next operation. Therefore, I have provided improved means for accomplishing this result, which means I will now describe.

Rotatably mounted on the shaft 13 is a slideable sleeve 61 having a reduced end. Secured thereon by means of a screw threaded nut 63 is a race 62. Mounted in the race on ball bearings is a collar 64. The opposite end of the sleeve 61 has keyed thereto a clutch pulley 65 which pulley is geared or connected to a source of power (not shown), in a manner to cause it to rotate at a considerably greater speed than the pulley 16 so that when the pulley 65 is thrown into engagement with the clutch 14 (by means presently to be described) the shaft 13 is caused to rotate at a very high speed while the pulley 16 continues to run idly. For throwing the shaft 13 into high speed the moment the cutting tools have completed one operation to quickly re-set the parts and back again into low speed the moment the tools are ready for the next operation, I have provided im-

proved means which can be readily and quickly adjusted and timed for this purpose, to which I will now refer.

Mounted on the cam shaft 22 near its upper end is a disk wheel 66. This wheel is provided with two circular grooves 67 each having a circular opening 68 carrying a screw threaded lug 69. Each lug has secured thereto by means of a nut or the like suitable trips 70 and 71 extending slightly beyond the periphery of the wheel 66 as best seen in Fig. 8. Referring to the same figure, there is mounted on the frame of the machine by any suitable means, a bracket 72 provided with aligned bearings. In these bearings is mounted a shaft 73 having fixed thereto a member 74 with two upwardly outwardly curved arms 75 provided with screw threaded pins 76 near their upper ends adapted to engage the collar 64. (Fig. 4.) The bracket 72 (Fig. 8) is at its upper outer end provided with bifurcated arms 76^a having aligned openings in which is pivotally mounted a locking lever 77. This locking lever at its free end is provided with a beveled pin 78 adapted to be engaged by the trip 70 on the wheel 66. The member 72 has an outwardly extending spring supporting arm terminating in a comparatively wide flat extension 79 which is provided with a pair of screw threaded openings. One of the arms 75 is integrally provided with an outwardly extending bell crank 81. This bell crank is provided with a pin near its outer end adapted to be engaged by the trip 71 on the wheel 66. Mounted between the outer end of the bell crank 81 and the spring supporting arm 79 are compression springs 80, both of which are adjustable by means of the screws 82 to increase or diminish the effective force of such springs. The pins near the outer ends of the locking lever 77 and bell crank 81 are readily adjustable by means of the set screws 82^a as shown. In Fig. 9 the locking lever 77 and bell crank 81 are shown in their normal position, that is, when in that position the high speed clutch 65 is out of operative engagement with the clutch 14. As the disk wheel 66 revolves the trip 70 engages the pin on the locking lever 77 (it will be understood that this trip is so adjusted on the wheel 66 as to come into engagement with the pin on the locking lever 77 the moment the cutting tools have completed their operations) and forces the locking lever 77 to swing downwardly. In so doing the quarter round pin 83 on the lever 77 which is in engagement with a similar pin 84 on the bell crank 81 becomes disengaged due to the different arc described by each, thus unlocking the bell crank 81, whereupon the inner compression spring 80 throws the free end of the bell crank upward causing the arms 75 to swing about their pivot and the collar 64 forcing the pulley 65 through the sleeve 61 into operative engagement with the clutch 14. Then when the trip 71 on the wheel

66 reaches the pin on the bell crank 81, it is likewise forced downwardly and through the same connection the pulley 65 is disengaged from the clutch 14. As the bell crank 81 is being moved downwardly the pin 84 describes an arc which permits the pin 83 to move upwardly to locking position as shown in Fig. 10.

I will now describe the stock magazine and the timing mechanism for automatically operating the magazine and for feeding the stock therein contained continuously and successively into the spindle. The magazine comprises a plurality of long parallel tubes 85 constituting barrels. In the embodiment shown they are positioned at the same angle as the spindle of the machine. The upper ends of the barrels 85 are mounted in and pass through a disk 86 which disk is rotatably mounted in a head 87. The head 87 is supported in the desired position by any suitable frame-work (not shown). The opposite ends of the barrels 85 are mounted in suitable openings in the gear wheel 88. This gear wheel as well as the disk 86 are non-rotatably mounted on a shaft 89. The inner or lower end of said shaft is suitably mounted in the head piece 90. The head piece in turn is suitably supported by the bed or frame of the machine. The head piece 90 is provided with a stock receiving opening 91 in alignment with the tube 29 of the spindle. On the upper side of the head 90 is an arc shaped beveled faced cam or race 92 which terminates at its greatest thickness in a bifurcated end at the opening 91. In practice the magazine is loaded by inserting pieces of stock in each of the barrels 85 which stock passes by gravity down the barrels until checked by the head piece 90. The entire magazine is revolved slowly by the shaft 93 which is provided with gear teeth designed to mesh with the gear 88. As the magazine is rotated the stock or rather the lower ends thereof, are caused to ride up on and past the arc shaped cam 92. The moment a piece of stock reaches the bifurcated end of the cam it starts on its downward travel through the receiving opening in the head piece into the spindle. Further rotation of the magazine is automatically stopped, by the means hereinafter described, until the entire supply in one barrel has passed therethrough.

Secured to the head 90 is a bracket 94 which bracket and head are provided with aligned bearings in which bearings is mounted the shaft 93. Rotatably mounted on this shaft on the lower side of the head 90 is a driving pulley 95 which pulley is operatively connected by a suitable belt 96 to a pulley 97 non-rotatably mounted on the cam shaft 22 as best shown in Figs. 2 and 8.

Mounted on the bracket 94 by any suitable means, is a cylindrical cup shaped casing 98, which casing is provided at its upper surface with a slot or groove 99 parallel with the

axis thereof. (See Fig. 13.) Keyed to the shaft 93 within this cup shaped casing is a disk 100 having a transverse slot or groove in which slot is pivotally mounted a dog 101 by means of the pin 102. This dog when thrown outwardly by means presently to be described, is adapted to register with the pins 103 fast to the inner surface of the pulley 95, so that when the dog is thrown out into the path of these pins the pulley 95 which is constantly rotating when the machine is in operation, rotates the magazine through the gear 88, shaft 93 and disk 100. The dog 101 is provided with an upwardly extending pin 104 (see Figures 16 and 17), adapted to register with, and travel in the annular groove 105 formed in the casing surrounding the disk. Mounted on the casing is an upwardly extending bracket 106 in which bracket is rigidly fixed a sleeve 107 (see Figures 11 and 12). In this sleeve is rotatably mounted a rock shaft 108. Rigidly fixed to one end of this rock shaft is a bifurcated arm or lever 109 so positioned as to be rocked or moved inwardly by the flanged sleeve 110, slideably mounted in the stock receiving opening 91 of the head 90. The stock on its travel to the spindle passes through the sleeve 110 thence through the bifurcated end of the arm 109. The outer or intake end of this sleeve is interiorly beveled as best shown in Fig. 11, to serve as a guide to direct the stock into the sleeve. For sliding the sleeve inwardly to operate or rock the bifurcated arm 109 there is inserted in each of the barrels 85 immediately after the stock has been placed therein a follower or plunger 111, of larger diameter than the stock so that when the outer end of the stock leaves the barrel 85 the follower, which operates by gravity moves downwardly and engages the outer end of the sleeve 110 moving it inwardly thus rocking the bifurcated arm 109. Fast to the opposite end of the rock shaft 108 is a trip lever 112 the free end thereof being adapted to swing in the transverse slot of the casing. Pivotally connected to this lever, intermediate its ends (see Figure 14), is a link 113. The free end of this link is off-set so as to be directly in line with, and in the path of the free end of the lever 112. Thus, when the lever 112 is thrown outwardly by the means heretofore described, it strikes the link 113, which in turn engages the pin 104 on the dog throwing the latter outwardly into the path of the pins on the pulley 95.

The moment the follower 111 moves out of contact with the sleeve 110 as the magazine rotates, the tension spring 114 automatically returns the sleeve and its cooperating levers to their normal position ready for the next operation.

The relation of the gearing and spacing of the tubes 85 in the magazine is such that the disk 100 makes one revolution from the time

the follower engages the sleeve and the next tube is brought into registration with the sleeve at which moment it is necessary to automatically throw the means for rotating the magazine out of engagement which means I will now describe.

Pivotally mounted on the casing is a lever 115 adapted to swing in the transverse slot of the casing. This lever near its free end is provided on its under side with a beveled cam groove 116 (see Fig. 17). This cam is adapted to be engaged by the pin 104 on the dog, as a result this pin in riding over the cam throws the dog into the position shown in dotted lines (Fig. 14) thus throwing the disk 100 out of driving relation with the pulley 95.

In order to re-set or return the lever 115 to its normal position after the pin has passed the cam thereon, I have provided a tension spring 117 which is suitably connected at one end to the casing and at its opposite end to the lever as best shown in Fig. 13. To limit the outward throw of the link 113, I have provided a stop pin 118 mounted in the transverse slot of the casing (see Fig. 13). For holding the disk in frictional registration with the casing and against accidental rotation, I have provided in the casing a spring pressed pin 119 having a beveled end adapted to cooperate with a beveled notch on the inner surface of the disk.

If for any reason the tension spring 114 should fail to function I have provided a cam 120 on the disk 100 adapted to engage the lower end of the link 113 and return it to its normal position.

For limiting the inward throw of the sleeve 110 by the follower 111 to the thickness of the bifurcated end of the cam race 92 I have provided a stop 121 secured by means of a bolt or the like to the head piece 90.

From the foregoing description it will be seen that I have provided a machine which possesses to the fullest extent all of the features heretofore pointed out as well as many other inherent advantages.

Assuming the parts are assembled as described and illustrated the operation briefly is as follows:

The various barrels of the magazine are filled with stock, one of which barrels is brought into registration with the receiving opening in the head 90 and thence feeds at an angle of about 40 degrees by frictional gravity down through the frictional stationary tube mounted in the spindle until the lower end of the stock engages the stock gauge 26 on the stock shaft 25. Assuming also that the machine is in operation and the various parts are timed and are in step with one another and that the spindle has gripped the stock and the cutting tools 47 are working on that portion of the stock extending beyond the spindle the parts are so timed that the rollers carried by the bell crank arms of the

tool heads leave their respective cams the moment the tooling operation is completed, whereupon the tools are thrown to open or idle position by the compression springs 58. Immediately upon completion of the tooling operation the trip 70 on the wheel 66 carried by the cam shaft 22 releases the locking lever 77, whereupon the shaft 13 is thrown into operative connection with the high speed driving pulley 65, which, through the connections theretofore described, causes the cam shaft to operate at high speed for resetting the machine. While the machine is operating at high speed the drum 45 through its cams throws the collar 40 back and forth for releasing and reestablishing the grip of the spindle. During the slight interval between the releasing and reestablishing of the grip of the spindle the stock gradually feeds by frictional gravity down the tube within the spindle, presenting a new section of stock for the tools to work on. Immediately thereupon the cams for operating the tool heads are so positioned as to bring the tools into cutting action with the portion of the stock extending beyond the spindle. The instant the tools are again brought into contact with the stock the trip 71 on the wheel 66 is so timed as to force the bell crank 81 downwardly, releasing the pulley 65 from the clutch 14 and thereby disconnecting the cam shaft from the high speed pulley and permitting it to return to low speed until the rollers carried by the arms on the tool heads again pass their respective cams, whereupon the high speed or reseating operation is again repeated.

While the foregoing operation is taking place the stock magazine delivers or feeds to the machine the various separate pieces in continuous succession, much in the same manner as though they were one long piece. The magazine is driven from a wheel on the cam shaft by means of an idler mounted on the shaft 93. This idler is thrown into and out of driving relation with a disk mounted on the shaft 93 by means of a pawl arrangement. This pawl is thrown into driving relation by engagement of the follower in the barrels of the magazine with the slideable sleeve 91 which in turn kicks or engages the lever 109 for throwing the pawl out of and into driving relation, which pawl is on each revolution returned to its normal position by means of the cam arrangement heretofore described.

Having thus described my invention, I claim:

1. In a screw machine, a plurality of stock retaining means, a frictionally controlled gravity feeding means for the stock, a stock follower slideable in one said retaining means, and means actuated by said follower for registering the next succeeding retaining means with said stock feeding means.

2. In a screw machine a feeding magazine

comprising a plurality of stock retaining means, a follower slideable in one of said retaining means, a tool, frictionally controlled gravity feeding means for feeding the stock to said tool, means actuated by said follower for successively registering each said retaining means with said feeding means, the stock being fed from said retaining means into said feeding means by gravity.

3. In a variable speed driving mechanism, a trip member, means for moving said trip member, a low speed and a high speed driving means operatively connectable with the trip moving means, and means including a locking lever actuated by said trip member for operatively connecting said high speed driving means to said trip moving means.

4. In a variable speed driving mechanism, a trip member, means for moving said trip member, a high speed driving means and a low speed driving means operatively connectable with said trip moving means, means actuated by said trip member for operatively connecting said high speed driving means with said trip moving means, and means actuated by said trip member for operatively disconnecting said high speed driving means from said trip moving means.

5. In a variable speed driving mechanism, a trip member, means for moving said member, a low speed driving means including a locking lever normally operatively connected with said trip moving means, and means actuated by said trip member for disconnecting said low speed driving means from said trip moving means.

6. In a screw machine, comprising a head provided with a stock receiving opening, a slideable bushing mounted in said opening through which the stock is adapted to pass, a magazine comprising a plurality of barrels adapted to successively register with said bushing, means for driving said magazine, a clutch mechanism adapted to be operated by the inward movement of said bushing, and a follower in said barrels for engaging and moving said bushing inwardly for the purpose set forth.

7. In a screw machine, the combination of a head having a stock intake opening, a magazine comprising a plurality of barrels adapted to successively register with said intake opening, means for rotating said magazine and a beveled cam race terminating at said intake opening for the purpose set forth.

8. In a screw machine, the combination of a head provided with a stock receiving opening, a rotatable magazine provided with a plurality of barrels adapted to successively register with said opening, a follower in said barrels, a gear on said magazine, a shaft connected with said gear, a driving wheel loosely mounted on said shaft, a casing, a member within said casing and rotatable with said shaft, a dog pivotally mounted in said member,

means operated by said follower for automatically throwing said dog into driving relation with said driving wheel when the stock is exhausted from any one of said barrels, and 5 means for automatically throwing said dog out of driving relation with said driving wheel when the next adjacent barrel has been brought into registration with said receiving opening, for the purpose set forth.

10 9. In a device of the class described, a driving and clutch mechanism comprising in combination, a shaft, a driving member rotatably mounted thereon, a casing, a disk non-rotatably mounted on said shaft within the casing, a 15 dog pivotally mounted in said disk and adapted to be thrown into driving relation with said driving member, a pin carried by said dog and a cam lever adapted to co-operate with said pin for disengaging said dog upon the completion of one revolution of said disk, for 20 the purpose set forth.

10 10. In a variable speed driving mechanism, comprising in combination a driving shaft, a clutch on said shaft, a driving member on one 25 side of said clutch, an independent driving member on the opposite side of said clutch, a spring actuated rocking arm connected with said independent driving member for operating said clutch, a locking lever for said 30 rocking arm, a driven member, and means operated by said driven member for releasing said rocking arm and returning it to locked position, substantially as set forth.

11. In a screw machine, the combination 35 of a cam shaft, pivotally mounted tool heads adjacent thereto, each provided with offset integral arms, independently adjustable cams on said shaft and adapted through suitable connections to rock said arms for the purpose 40 set forth.

12. In a screw machine, a cam shaft in combination with means for operating the tool heads, said means comprising a drum fastened to the cam shaft, a pair of independent 45 and readily adjustable cams provided with annular grooves and a pair of disks provided with tongues adapted to co-operate with said grooves, and means for readily securing said disks, cams and drum together, for the purpose 50 set forth.

13. In a screw machine a cam shaft, a plurality of cams each having a circular hole therethrough for concentric mounting on said shaft, concentric grooves on said cams, and 55 means rigidly connected to said shaft and projecting into said grooves for locking said cams in a plurality of positions.

14. In a screw machine, comprising a bed positioned at a substantial angle, a rotatable 60 spindle mounted thereon and parallel with said bed, and a non-rotatable frictional feed tube mounted in said spindle, substantially as and for the purpose set forth.

15. In a variable speed mechanism, a rotatable shaft, a clutch non-rotatably mounted on

said shaft, a driving wheel rotatable relatively to said clutch, means for engaging said wheel and clutch, said means automatically operating when the wheel rotates relatively to the clutch in one direction, and a second driving wheel rotatable relatively to the clutch and movable longitudinally into operative engagement with the clutch. 70

16. In a variable speed mechanism, a rotatable shaft, a clutch non-rotatably mounted on said shaft, a driving wheel rotatable relatively to said clutch, means for engaging said wheel and clutch, said means automatically operating when the wheel rotates relatively to the clutch in one direction, and a second driving wheel rotatable relatively to the clutch, and means for moving the second wheel longitudinally into operative engagement with said clutch. 75

17. In a device of the class described, a driving shaft, a driving clutch for said shaft, a driving member for said clutch, a bell crank operatively connected with said driving member, means cooperating with said bell crank for throwing said driving member into driving relation with said clutch, a locking lever cooperating with said bell crank for holding said driving member out of driving relation with said clutch, and means for automatically releasing said bell crank and returning it to its locked position. 85 90

18. In a screw machine, the combination of a rotatable spindle mounted therein, and a non-rotatable tube mounted in said spindle for feeding stock operated on, substantially as 100 and for the purpose set forth.

19. In a variable speed mechanism, a driving shaft, a driving clutch for said shaft, a driving member for said clutch, a pivoted element for moving said driving member, means 105 cooperating with said element for throwing said driving member into driving relation with said clutch, a locking lever cooperating with said pivoted element for locking said element and for holding said driving member out of driving relation with said clutch, and means for automatically releasing said element and returning it to its locked position. 110

20. In an adjustable cam mechanism, a 115 shaft, a cam, a supporting member for centering the cam about a shaft, and means for rigidly retaining the cam on said member, said means comprising a groove in said cam and a disk provided with a tongue fitting in 120 said groove.

21. In a clutch mechanism, the combination of a rocking arm provided with a locking pin, a locking lever arranged in a parallel plane and provided with a pin adapted to mesh with the pin on the rocking arm for holding said arm in locked position and means for releasing said arm and returning it to locked position. 125

22. In a clutch mechanism, the combina- 130

tion of a rocking arm spring actuated in one direction, a locking lever adapted to connect with said arm for holding in locked position and means for releasing said arm and returning it to locked position.

5 23. In an adjustable cam mechanism, a movable shaft, a cam supporting member non-rotatably mounted on said shaft, a cam rotatably mounted on said member, and
10 means for rigidly retaining the cam on said member, said means comprising an annular groove in said cam and a tongue fitting in said groove.

15 24. In an adjustable cam mechanism, a shaft, a cam, a supporting member for centering the cam about the shaft, and means for rigidly retaining the cam on said member in any position relative to a fixed diameter of the shaft, said means comprising a groove in said cam and a disk provided with a tongue fitting in said groove.

20 25. In an adjustable cam mechanism, a movable shaft, a cam supporting member non-rotatably mounted on said shaft, a cam rotatably mounted on said member, and means for rigidly retaining the cam on said member in any position relative to a fixed diameter of the shaft, said means comprising a groove in said cam and a disc provided with
25 a tongue fitting in said groove.

30 In witness whereof, I have hereunto subscribed my name to this specification.

X RAYMOND DODGE.

CERTIFICATE OF CORRECTION.

Patent No. 1,794,885.

Granted March 3, 1931, to

X RAYMOND DODGE.

It is hereby certified that error appears in the printed specification of the above numbered patent requiring correction as follows: Page 6, lines 96 and 97, claim 5, strike out the words "including a locking lever" and insert the same before the word "actuated" in line 99, of same claim; and that the said Letters Patent should be read with this correction therein that the same may conform to the record of the case in the Patent Office.

Signed and sealed this 5th day of May, A. D. 1931.

(Seal)

**M. J. Moore,
Acting Commissioner of Patents.**
